UNITED STATES PATENT OFFICE.

OSVALD E. RASMUSSEN, OF LINCOLN PARK, NEW JERSEY, ASSIGNOR TO WESTERN ELECTRIC COMPANY, INCORPORATED, OF NEW YORK, N. Y., A CORPORATION OF NEW YORK.

AUTOMATIC TELEPHONE SWITCH.

Application filed March 15, 1922. Serial No. 543,863.

To all whom it may concern:

Be it known that I, OSVALD E. RASMUSSEN, a citizen of the United States, residing at Lincoln Park, in the county of Morris, State of New Jersey, have invented certain new and useful Improvements in Automatic Telephone Switches, of which the following is a full, clear, concise, and exact description.

This invention relates to automatic switching apparatus and more particularly to coordinate switches of the type for establishing connections in an automatic telephone exchange system.

The present invention is an improvement 15 on the switch structure described in the British Patent 183,436, issued to Western Electric Company, Limited, accepted August 23, 1923, which is directed to a switch structure having operating cards for 20 moving sets of active contacts into engagement with sets of passive contacts, the operating cards being supported on flexible springs and arranged to be moved through the conjoint operation of actuating bars.

In the above noted switch structure the flexible supporting springs being rigidly attached to both the operating cards and to supports attached to the framework of the switch structure, provide a semi-rigid 25 support for the cards, it being necessary in lifting or moving a card to flex the springs not only against their own inherent resistance to flexure but also against the tendency of the card and support to hold them in their 30 normal unflexed position. In other words, to lift a card it is necessary to warp the entire card support comprising the supporting springs and their rigid connection at their free ends through the card which they 35 support. A greater amount of energy is therefore required to operate a card than would be required if the card were more freely supported.

The principal object of this invention, 40 therefore, is to provide a switch structure of the character above described wherein the contacts are brought into engagement in a positive manner with the expenditure of a small amount of energy.

A further object of the invention is to 45 provide simple and efficient means for guid-

ing the contact operating cards in such a manner that they may be easily actuated.

A still further object is to provide means whereby a connection once made may be 55 maintained undisturbed while subsequent connections are being effected.

The principal feature of the invention consists in the combination of normally disengaged contacts, operating cards for effecting the engagement of the contacts, and conjointly operating coordinate bars for operating said cards, with members for guiding the cards whereby said cards are freely movable under the control of the coordinate 60 bars. Other features of the invention will be apparent from the following detailed 65 description and the attached drawings.

The preferred form of the invention is illustrated in the accompanying drawing 70 in which Fig. 1 is a front elevational view of a coordinate switch with the features of this invention embodied therein; Fig. 2 is a side view of Fig. 1; Fig. 3 is a section on the line 3—3 of Fig. 1; Fig. 4 is a section 75 on the line 4—4 of Fig. 1 and Fig. 5 is a detail of a portion of the mechanism associated with one of the horizontal operating bars of the switch in its various stages of 80 operation.

In order not to complicate the drawing, only one set of parts disclosed in Fig. 1 is identified by reference numerals, it being understood that where an element or a part of the figure is not identified, its structure 85 and functions are the same as similar elements identified elsewhere on the figure.

The sets of grid or passive conductors 1, 2, 5 and 6 are securely fastened at their ends to fixed members (not shown) forming 90 a portion of the supporting frame 41 of the switch and are preferably woven in and out between insulating strips (not shown) in the manner disclosed in the aforementioned application.

A support 11 (Fig. 2) of insulating material also suitably secured to the frame of the switch, is provided for each row of sets of flexible wire contact springs or active conductors 7, 8, 9 and 10. These supports 100 are disposed at right angles to the direction of the length of the grid conductors. The

support 11 may be of considerable length and may carry any number of sets of contact springs depending upon the switch capacity desired. The free ends of each set of contact springs 7, 8, 9 and 10 extend through oblique apertures 12 in a tie member or operating card 13, each of said cards being removably engaged in a channel-shaped guide 40 consisting essentially of the walls or flanges 14 and 15. These guide channels 40 are secured in any suitable manner on the frame 41. The card 13 is provided with a projection 16 which extends into the slot 17 in the wall 14 of the guide 40, and with a pin 37 extending through a slot in the wall 15 of the guide 40, thereby permitting the card to move freely and at the same time be held in position in the guide. The card 13 is normally arranged in the guide to hold the contact springs out of contact with the grid conductors.

18 and 19 are two coordinately disposed bars, the bar 19 being free to move vertically a limited distance under the influence of armature 20 of electro-magnet 21, its movement being limited by the bolts 22 which extend through the apertures 23 in the bar 19 and into supporting lugs 42 integral with the guide 40. Bar 18 is free to move laterally under the influence of armature 24 of magnet 25 and is provided with a series of sets of collars 26 and 27, a set of collars adjacent each vertical bar 19. The collar 26 is provided with a pin or projection 28 and is so constructed as to be free to rotate on bar 18 but is restrained from any lateral movement thereon as shown in Fig. 4. The collar 27 is permanently fixed to the bar 18 by the screw 29. Interposed between collars 26 and 27 and permanently attached to both is a spring 30, the function of which is to restore collar 26 to its normal position on bar 18 after it has been rotated.

An L-shaped lever 31 is fulcrumed at the point 32 on the lug 43 integral with the guide 40, the downwardly extending portion of lever 31 being adapted to be engaged by pin 28. Upon the lateral movement of bar 18, the lever 31 rotates about its fulcrum 32 causing its laterally extending portion to travel upwardly. This upward movement is transmitted to the card 13 since the lever 31 is in constant engagement with the card 13 at the point 33.

Restoring springs 34 and 35 are provided for restoring bars 19 and 18 to normal position upon the deenergization of the magnets 21 and 25, respectively. 36 is a restoring spring attached to the pin 37 and to the lug 43 for returning card 13 to normal upon the deenergization of magnet 25 and the consequent restoration of lever 31.

The bar 19 is provided with a series of lateral arms or projections 38 adapted to engage the pins 28 upon the actuation of

said bar for rotating them with respect to the bars 18. The pins 28 are guided during their lateral movement by guides 39 formed integrally with the channel guide 40.

Referring to Fig. 1, the lower left portion of which shows the device in its normal condition with the pin 28 and lateral projection 38 disengaged as at A, the operation of the switch is as follows: Upon the energization of electromagnet 21 which, for example, may be brought about in response to an incoming call, armature 20 is attracted and moves selecting bar 19 upwardly causing collar 26 to rotate on bar 18 due to the engagement of projections 38 with pins 28 moving the pins 28 into the position shown at B. Magnet 25 is now energized attracting armature 24 and driving the bar 18 in a horizontal direction. This action transfers the pin 28 from the lateral projection 38 to the guide 39 and the pin 28 is held thereon due to the tension of spring 30. In this movement, the pin 28 has engaged the lever 31, as shown at C. The lever 31 being fulcrumed at 32 rotates about this point causing the card 13 engaged thereby to be moved upwardly along the guiding walls 14 and 15 of guide 40. The contact springs 7, 8, 9 and 10 are thereby brought into electrical contact with the grid conductors 1, 2, 5 and 6, respectively. This connection is not released upon the deenergization of magnet 21 as long as magnet 25 remains energized. The remaining pins 28 carried by the operated bar 18 are at this time ineffective to operate associated levers 31, since they have not been displaced by projections on other bars 19 and therefore move beneath the guides 39. The released bar 19 may be subsequently operated to effect the establishment of other connections at contact sets served thereby in cooperation with another bar 18, inasmuch as the pin 28 employed in an established connection is out of the path of the corresponding projection 38 on bar 19 and therefore the existing connection is not disturbed.

Upon the deenergization of magnet 21, the restoring spring 34 returns bar 19 to its normal position. When the connection previously effected is no longer desired, the magnet 25 is deenergized and the spring 35 operates to restore bar 18 to its normal position and spring 36 at the same time returns card 13 to its normal position. The return of bar 18 to normal causes pin 28 to slide off the guide 39 thereby releasing the tension in spring 30 causing the collar 26 attached thereto to return to its normal position.

Should a horizontal bar 18 be released while a bar 19 such as the bar at the left of Fig. 1, is in its operated position, the idle pins 28 on the bar 18 will pass beneath the corresponding projections 38 on the bar

19 and will, upon the subsequent release of bar 19, be depressed against the tension of spring 30 into the lowermost dotted position shown in Fig. 5, whereupon the depressed 5 pins will be released from the projections 38 and move to their normal positions as indicated by the intermediate dotted line position shown in Fig. 5. Thus, the apparatus is in no manner rendered ineffective 10 due to the particular order in which the several parts are released.

What is claimed is:

1. In a switching mechanism, a set of contacts, an operating member therefor, a 15 channel-shaped guide for said operating member, and means comprising conjointly operating bars for moving said operating member in said guide.
2. In a switching mechanism, a set of 20 contacts, an operating card therefor, a channel-shaped guide for said operating card, and means comprising conjointly operating bars for moving said operating card in said guide.
3. In a switching mechanism, a plurality 25 of sets of contacts, operating cards therefor, a channel-shaped guide in which said cards are disposed, and means for independently moving said cards in said guide.
4. In a switching mechanism, a plurality 30 of sets of contacts, operating cards therefor, a channel-shaped guide in which a plurality of said cards are disposed, and means comprising conjointly operating bars for independently moving said cards in said guide.
5. In a switching mechanism, a plurality 35 of sets of contacts, operating cards therefor, a channel-shaped guide in which said cards are disposed for movement, and means comprising conjointly operating bars for independently moving said cards in said guide.
6. In a switching mechanism, a set of 45 contacts, an operating member therefor, a channel-shaped guide arranged for a plurality of said operating members, means for moving said operating members in said guide, and restoring means for said members.
7. In a switching mechanism, a set of 50 contacts, an operating member therefor, a channel-shaped guide arranged for a plurality of said operating members having slots in its flanges, means carried by said 55 members and engaging in said slots for retaining said members within said guide, and means for moving said members in said guide.
8. In a switching mechanism, a plurality 60 of sets of conductors, a plurality of sets of contacts cooperating therewith arranged in rows, an operating card for each of said sets of contacts, channel-shaped guides in which the cards of each of said rows are 65 disposed, an operating bar for each of said

sets of conductors, an operating bar for each of said rows of contacts, and means for operating said bars conjointly to move said cards in said guides.

9. In a switching mechanism, sets of active and passive contacts coordinately disposed, an operating card for each set of active contacts having a series of apertures, said active contacts extending through said apertures, a guide for said operating cards, a selecting bar having a plurality of lateral arms, an actuating bar disposed at right angles to said selecting bar, a series of pins on said actuating bar, and means for moving one of said operating cards in said 70 guide upon the conjoint operation of said bars through the engagement between an arm of said selecting bar and a pin on said actuating bar thereby effecting engagement 75 between said sets of active and passive contacts.

10. In a switching mechanism, a plurality of sets of conductors arranged in parallel rows, a plurality of sets of movable contact members arranged in rows coordinate to said 90 rows of conductors, a frame, a bar having a plurality of lateral arms, said bar slidably attached to said frame, a second bar arranged coordinately to said first bar, a series of pins on said second bar, means for operating said first bar to effect the engagement of an arm thereon with a pin on said second bar, and means comprising a pivoted lever responsive to the subsequent operation of said second bar to effect engagement 95 between a set of said conductors and a set of said movable contact members.

11. In a switching mechanism, a plurality of sets of conductors arranged in parallel rows, a plurality of sets of movable contact members arranged in rows coordinate to said rows of conductors, an operating card for each set of contact members having apertures for maintaining said movable contact members in spaced relation from 100 said conductors, a guide for said cards, an actuating bar, means for moving said bar, means for transmitting the movement of said bar to said operating card, and means for restraining the movement of said operating card in said guide.

12. In a switching mechanism, a plurality of sets of stationary conductors, a plurality of rows of movable contact members disposed coordinately to said stationary conductors, each of said rows of movable contact members divided into a plurality of sets and each set of each row associated with a different set of stationary conductors, an operating card having a series of apertures admitting a set of said movable contact members, a guide for said operating card, selecting bars coordinately disposed, and means for operating said selecting bars for causing movement of said 120 125 130

- operating card in said guide to effect engagement between one of said sets of stationary conductors and one of said sets of movable contact members.
- 5 13. In a switching mechanism, a fixed contact bank comprising a plurality of sets of parallel conductors, a plurality of sets of movable conductors arranged in rows at right angles to said bank conductors and 10 extending through said bank, each movable conductor crossing one of said bank conductors but normally out of contact therewith, a movable support for each set of movable conductors, guides for the movable 15 supports, a plurality of selecting bars each having lateral arms disposed at regular intervals thereon equal in number to the sets of movable conductors in a row, a series of actuating bars coordinately disposed to said 20 selecting bars and having a plurality of pins thereon equal in number to the rows of movable conductors, means for operating said selecting bars individually, means for operating said actuating bars individually, 25 and means for operating one of said movable supports responsive to the conjoint operation of one of said selecting bars and one of said actuating bars through the engagement between a lateral arm of one of 30 said selecting bars and a pin on one of said actuating bars thereby establishing a connection between a set of movable conductors and a set of bank conductors at their crossing point.
- 35 14. In a switching mechanism, a plurality of sets of contact springs arranged in a row, a set of stationary conductors for each of said sets of contact springs, a movable support for each set of contact springs, a guide 40 for said movable supports, and means for actuating one of said movable supports in said guide comprising a vertically movable bar having a lateral arm extending therefrom, a laterally movable horizontal bar 45 having a pin thereon for engagement with the lateral arm on said first bar, and an L-shaped lever fulcrumed at its mid-point, one end thereof engaging said movable support and the other end adapted to be 50 engaged by said pin on said horizontal bar upon the vertical movement of said first bar and the subsequent movement of said second bar to impart vertical movement to said 55 movable support.
- 55 15. A switch structure comprising a plurality of sets of contact springs arranged in rows, a plurality of rows of sets of fixed conductors disposed coordinately to said first mentioned rows, each of said sets of 60 contact springs of a row associated with one of said sets of fixed conductors, a movable tie member for each of said sets of contact springs, guides for said tie members, coordinately disposed sets of operating bars, the bars of one set being individual respectively to the rows of contact sets and provided with lateral arms projecting therefrom and the bars of the other set being individual respectively to the rows of sets of conductors and provided with collars, said collars having pins extending therefrom and being free to rotate on said bars upon engagement between the lateral arms of said first set of bars and the pins on said collars, means for limiting the rotation of said collars and returning them to normal upon disengagement of the pins on said collars from the lateral arms on the first set of said bars, electromagnetic means for conjointly operating both of said sets of bars for causing said tie members to move in said guides to effect engagement between the sets of fixed conductors and the sets of contact springs operated by said tie members, and means individual to the bars of each set for restoring said bars to normal upon deenergization of said electromagnetic means. 70
- 75 16. A switch structure comprising a set of contact springs, a set of fixed conductors disposed coordinately to said first mentioned set and associated therewith, an operating card for said set of contact springs, a guide for said operating card, coordinately disposed operating bars, one of said bars provided with a lateral arm thereon, the other of said bars provided with a collar having a pin extending therefrom, said collar being free to rotate on said bar upon engagement of said lateral arm with said pin, individual electromagnetic means for operating said bars, and means effective upon the conjoint operation of said electromagnetic means to cause said operating card to move in said guide and effect electrical connection between said set of contact springs and said fixed conductors, said connection being maintained by the continued energization of one only of said electromagnetic means. 80
- 85 17. In a switching mechanism, normally disengaged contacts, a pair of coordinately disposed bars, a resiliently mounted pin carried by one of said bars, an arm carried by the other of said bars, means for operating the first mentioned bar to move said pin, and means for operating the second mentioned bar to move said arm, a movement of said arm followed by a movement of said pin being effective to interengage 90 said contacts, said engagement being unaffected during its continuation by subsequent operations of said second mentioned bar. 95
- 100 18. In a switching mechanism, normally disengaged contacts, a pair of coordinately disposed bars, a rotatable collar upon one of said bars having a projecting pin, an arm carried by the other of said bars, means for operating said first mentioned bar to 105 110
- 115 120
- 125 130

move said pin, and means for operating the second mentioned bar to move said arm, a movement of said pin prior to the movement of said arm being ineffective to inter-
5 engage said contacts, and a movement of said arm followed by a movement of said pin being effective to engage said contacts,

said engagement being unaffected by subsequent operations of said second mentioned bar.

In witness whereof, I hereunto subscribe my name this 11th day of March A. D., 1922.

OSVALD E. RASMUSSEN.
